UNITED STATES PATENT OFFICE.

LEWIS M. CLEMENT, OF OAKLAND, AND GEORGE C. WATRISS, OF SAN FRANCISCO, CALIFORNIA.

GRIP FOR CABLE STREET-RAILWAYS.

SPECIFICATION forming part of Letters Patent No. 391,511, dated October 23, 1888.

Application filed May 23, 1888. Serial No. 294,865. (No model.)

To all whom it may concern:

Be it known that we, LEWIS M. CLEMENT, of Oakland, Alameda county, State of California, and GEORGE C. WATRISS, of the city and county of San Francisco, State of California, have invented a certain Improvement in Grips for Cable Street-Railways, of which the following is a specification.

Our invention relates to the cable-gripping apparatus; and it consists in an improved arrangement of the jaws thereof in connection with the operating mechanism, by which the cable may be released and dropped upon the carrying-pulleys by the act of opening the jaws apart and without the intervention of mechanism to throw aside either the cable or the grip from their normal alignment, while at the same time the grip-jaws and their operating mechanism may freely pass the ordinary depression-pulleys set at the vertical angles where the road suddenly rises upon an upward grade without any mechanism being used to set aside either these depression-pulleys to give passage to the grip or the grip to escape contact with the pulleys.

In the accompanying drawings, forming a part of this specification, Figure 1 is a transverse sectional elevation of a road-bed and subway with our invention applied therein. Fig. 2 is a side elevation of the grip, illustrating the means for operating the jaws. Fig. 3 is a plan of the lower part of the grip below the line *x y* in Fig. 2. Fig. 4 is a perspective view of the grip-jaws, showing how they interlock with each other.

In all the figures the same letters of reference are used to indicate the same parts.

In Fig. 1, A is the cable-subway, the particular construction of which it is not necessary to describe, as any of the various systems of construction will answer. B are the track-rails. C is the axle, and C' are the wheels of the car, to the body of which the grip is secured. D is one of the series of cable-carrying pulleys. E is the depression-pulley, and F is the cable. All of these parts are as now in use, and no change in their form or operation is involved in this present invention.

G is the grip, the main feature of our improvement in which relates to the jaws, which

are arranged to open apart vertically to drop the cable out from between them from below and freely pass the depression-pulleys.

g is the stationary frame of the grip, secured in any of the known ways either to the axles or to the floor of the car. This stationary frame has the usual notched quadrant at its upper end and carries one of the grip-jaws, *g'*. This jaw *g'* may either form part of the frame *g*, or it may be a separate piece bolted thereto. It will, however, be stationary with relation to the grip-frame and project considerably sidewise therefrom. The opposing jaw, *g''*, is a vibrating jaw, and is pivoted or hinged to the jaw *g'* similarly as the leaves of an ordinary door-hinge are connected together, there being a center boss or lug on the vibrating jaw projecting between the two end bosses on the stationary jaw, a pin, *g*³, being passed through the three bosses.

H is a vertically-moving flat bar guided between the two side legs of the grip-frame and the cross-bars *I*, which are secured to the car or axles, as before suggested. This bar *H* is pivoted at its lower end to the vibrating jaw *g''*, and its upper end is connected through the links *g*⁴ to the operating-lever *g*⁵.

The action is as follows: When the operating-lever is thrown in the direction of the arrow-point, the bar *H* is depressed and the grip-jaws are closed to grip the cable. The pawl of the operating-lever, engaging with the ratchet-teeth of the quadrant, holds the grip closed. When the cable is to be released, the pawl is disengaged, the lever drawn back, and the jaws opened apart. If the cable is to be but temporarily released, it is not necessary to open the jaws more than is sufficient to allow it to pass between the jaws; but if the cable is to be released for a considerable time the jaws should be opened enough to allow the cable to drop out entirely from between them to rest upon the carrying-pulleys. Because the grip-jaws are projected sidewise a considerable distance from the frame of the grip, as before stated, and as shown in the figures of the drawings, it is easy to pass all the depression-pulleys that may be upon the road. All that is necessary is to arrange that no part of these pulleys project within the path of the shank of the grip.

Of course we do not claim that a grip offset as ours is shown is in a broad sense new, for we are aware grips of this design have been in use for many years; nor do we claim any 5 novelty in the jaws being made to drop the cable from below, grips operating substantially the same in this respect to our grip having been long in use.

What we claim as our invention, and desire 10 to secure by Letters Patent, is as follows:

A gripping device for cable-railways, consisting, essentially, of a pair of gripping-jaws separating from each other upon a vertical line, one jaw being immovable with relation

to the grip-frame and secured to the immov- 15 able part thereof, and the other jaw being hinged to this immovable jaw and connected with and vibrated by the vertically-moving bar of the grip, both jaws being so offset from the grip-shank as to freely pass under the de- 20 pression-pulleys set outside the path of the grip-shank, in combination with suitable operating mechanism, substantially as described.

LEWIS M. CLEMENT.
